HEADSTOCK FOR COMBINATION POWER TOOL

John W. Edgemon, Jr., Los Altos, Calif., assignor to
Magna Engineering Corporation, Menlo Park, Calif., a
corporation of California

Application March 15, 1955, Serial No. 35,053

Term of patent 14 years

(Cl. D54—6)

FIG-3

FIG-4

Fig. 1 is a front elevation of a headstock for combination power tool embodying my new design; Fig. 2 is a right-hand end elevation thereof; Fig. 3 is a left-hand end elevation thereof; and Fig. 4 is a rear-side elevation thereof.

I claim:

The ornamental design for a headstock for combination power tool, substantially as shown.
